E. G. K. ANDERSON

THERMO STATICALLY CONTROLLED HEATING PLUG

Filed April 14, 1927

INVENTOR:
E. G. K. Anderson,

By Wm. F. Freudenreich, Atty

UNITED STATES PATENT OFFICE.

ERNST G. K. ANDERSON, OF EVANSTON, ILLINOIS, ASSIGNOR TO APPLETON ELECTRIC COMPANY, A CORPORATION OF ILLINOIS.

THERMOSTATICALLY-CONTROLLED HEATING PLUG.

Application filed April 14, 1927. Serial No. 183,826.

The present invention, specifically considered, relates to a stopper for a hot water bottle or the like and has for its object to produce a simple and novel construction by means of which the temperature of liquid in the bottle may automatically be maintained at a uniform temperature.

In carrying out my invention I make use of a plug having separated terminals adapted to dip into the liquid to be heated, and containing a thermostat that will open an electric circuit when a predetermined maximum of temperature is reached and thus shut off the energy for supplying the heat. Therefore, since the plug may be used for other purposes than as a stopper for a bottle or other container, my invention may be said to have for its object to produce a simple and novel liquid heater containing a thermostatic controller for regulating the heat.

The various features of novelty whereby my invention is characterized will herein-after be pointed out with particularity in the claims; but, for a full understanding of my invention and of its objects and advantages, reference may be had to the following detailed description taken in connection with the accompanying drawing, wherein:

Figure 1 is a side elevation through a device arranged in accordance with the preferred form of my invention; Fig. 2 is a central longitudinal section, on a larger scale on a plane at right angles to that of Fig. 1; and Fig. 3 is a section on line 3—3 of Fig. 2.

Referring to the drawing, 1 represents a body or plug of insulating material which, if the device is to be employed as a stopper for a bottle or other container, has a screw-threaded lower portion as indicated at 2. The extreme lower end of the plug is in the form of a tube or shell 3 smaller in diameter than the screw-threaded portion. Within this shell is a terminal 4 in the form of a sleeve, the upper end of which extends into the body of the plug. Openings or windows 5 and 6 are formed in the compound annular wall composed of the members 3 and 4, at diametrically opposite points. There is a second terminal 7 in the form of a comparatively heavy metal rod or post lying at the long axis of the annular terminal and projecting up into the body of the plug. The lower end of the terminal 7 pref-

erably lies inwardly some distance from the lower end of the annular wall that surrounds the same. Moreover, the material of the shell 3 is carried inwardly underneath the lower edge of the annular terminal. Consequently a person handling the device while the terminals are energized is not apt to receive a shock by touching both terminals and thus producing a short circuit.

Mechanically and electrically connected to the terminal 4 is a switch blade 8 that extends upwardly above the top of the plug. There is a similar switch blade 9 for the terminal 7, but this switch blade is not permanently connected to its terminal, the connection being adapted to be automatically made and broken to control the heat when the device is in use.

There is a chamber or well 10 opening down through the top of the plug at the center. The upper end of the terminal 7 extends into the bottom of this chamber or well. A suitable contact piece extends from the blade 9 into one side of the chamber or well; this contact piece being conveniently in the form of a small screw 11 extending through a screw-threaded hole in the switch blade; the plug having in one side a hole 12 through which the screw may be inserted; and the hole being filled with suitable plastic insulating material after the screw has been properly adjusted. Rising from the top of the terminal 7 is a thermal element 13 which, when its temperature is below a predetermined maximum, engages with the contact screw 11. When the temperature of the thermal element rises above a predetermined maximum value it bends in the well known manner so as to swing out of engagement with the contact screw, thus interrupting the flow of current if there has been current flowing. The terminal 7 must conduct heat to the thermal element, and it is therefore required to be of heat conductive material as well as being electrically conductive.

The remainder of the device consists simply of a head on the end of a cord or cable 14, whose purpose is to form a quickly detachable connection between the switch blades 8 and 9 and a source of electrical energy. In the arrangement shown, the head consists of a lower body 15 of insulating material and an upper body 16 fastened together by a screw 17. The member 15 has pockets extending up from the bot-

tom, as indicated at 18 and 19, to receive the projecting ends of the switch blades 8 and 9. Resilient contact fingers 20 and 21 extend from the member 16 down into the 5 pockets 18 and 19 in position to engage frictionally with the switch blades when the head is pushed down over the blades.

The upper part of the plug is preferably flattened at two opposed sides, as indicated 10 at 22 in Fig. 1, thereby producing a more or less rectangular head that may be gripped in the fingers for the purpose of screwing the plug into or out of a bottle or the like.

In using the device, it is placed so that 15 that part below the screw-threaded section is surrounded by the liquid to be heated. When the current is turned on it passes between the terminals 4 and 7, the liquid acting as a part of the circuit. The resistance 20 of the liquid is considerable and therefore heat is developed. The terminals of course become as hot as the liquid in contact with the same and, as the temperature of the middle terminal 7 rises and falls, so also 25 does the temperature of the thermal element 13. As long as the temperature of the liquid is below a predetermined maximum the thermally controlled switch remains closed but, when there is an increase 30 in the temperature above such maximum, the switch is automatically opened and the flow of current interrupted.

When a liquid is heated it expands, so 35 that the hotter liquid in a body rises to the top and cooler liquid settles. In the use of

my improved device, the liquid within the annular space at the bottom of the device rises as it is heated and flows laterally out through the windows 5 and 6, other cooler liquid being pressed up into the bottom of 40 this annular space by the greater liquid head on the outside where the top of the liquid is cooler than it is within the annular space. In this way a circulation of the liquid in a bottle or the like is maintained, 45 so that the entire liquid contents will be kept warm or hot as the case may be.

While I have illustrated and described with particularity only a single preferred form of my invention, I do not desire to be limited to the exact structural details thus illustrated and described; but intend to cover all forms and arrangements which come within the definitions of my invention 50 constituting the appended claim. 55

I claim:

A heating stopper for a liquid container comprising a stopper body of insulating material, a tubular terminal projecting downwardly from said body, the material 60 of the body being continued down around said terminal and underneath the free edge of the latter, a second terminal extending downwardly from said body at the center of the tubular terminal and having its lower 65 end lying at a considerable distance above the lower end of the tubular terminal.

In testimony whereof, I sign this specification.

ERNST G. K. ANDERSON.
